CLAIM

The ornamental design for an inflatable double lane water slide, as shown and described.

DESCRIPTION

FIG. 1 is a front, right side and top perspective view of an inflatable double lane water slide showing my new design; FIG. 2 is a rear, left side and bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof;

FIG. 8 is a front elevation view thereof; and,

FIG. 9 is an enlarged view of the selected portion 9 in FIG. 2.

The broken lines depict portions of the inflatable double lane water slide that form no part of the claimed design. The dot-dash broken lines depict the boundaries of the enlargements and form no part of the claimed design.

1 Claim, 9 Drawing Sheets
